FOOD STORAGE CONTAINER

Alvin W. Levenhagen, Pine Township,
Crawford County, Pa.

Application August 27, 1954, Serial No. 32,048

Term of patent 7 years

(Cl. D44—1)

Fig. 2

Fig. 4

To all whom it may concern:

Be it known that I, Alvin W. Levenhagen, a citizen of the United States, residing at Pine Township, in the county of Crawford and State of Pennsylvania, have invented a new, original, and ornamental Design for a Food Storage Container, of which the following is a specification, reference being had to the accompanying drawing, forming part thereof.

I claim:

The ornamental design for a food storage container, as shown.
